Primary Examiner — Shawn T Gingrich*Assistant Examiner* — Amanda Christensen(74) *Attorney, Agent, or Firm* — Anooj Patel; Kevin Schraven; Hankin Patent Law, APC(57) **CLAIM**

The ornamental design for a wireless appliance charging station, as shown and described.

DESCRIPTION

FIG. 1 is a perspective view of the wireless appliance charging station.

FIG. 2 is a top plan view thereof.

FIG. 3 is a bottom plan view thereof.

FIG. 4 is a front side elevation view thereof.

FIG. 5 is a rear side elevation view thereof.

FIG. 6 is a right end elevation view thereof; and,

FIG. 7 is a left end elevation view thereof.

The broken lines shown in the figures depict portions of the article that form no part of the claimed design.

1 Claim, 4 Drawing Sheets(56)
